(57) **CLAIM**

The ornamental design for a humming bird feeder, as shown and described.

DESCRIPTION

FIG. 1 is a first perspective view of a humming bird feeder showing my new design;
 FIG. 2 is a second perspective view thereof;
 FIG. 3 is a front view thereof;
 FIG. 4 is a back view thereof;
 FIG. 5 is a right side view thereof;
 FIG. 6 is a top view thereof;
 FIG. 7 is a bottom view thereof; and,
 FIG. 8 is a perspective view of another state of the humming bird feeder thereof.
